J. A. ZAHN,

IGNITER.

APPLICATION FILED APR. 22, 1921.

Patented Dec. 6, 1921.

Joseph A. Zahn, Inventor
By his Attorney, J. W. Barker

UNITED STATES PATENT OFFICE.

JOSEPH A. ZAHN, OF ASTORIA, NEW YORK, ASSIGNOR TO EMILY BERTHOLD, OF JAMAICA, NEW YORK.

IGNITER.

1,399,727.

Specification of Letters Patent.

Patented Dec. 6, 1921.

Application filed April 22, 1921. Serial No. 463,501.

To all whom it may concern:

Be it known that I, JOSEPH A. ZAHN, a citizen of the United States, and resident of Astoria, in the county of Queens and State 5 of New York, have invented certain new and useful Improvements in Igniters, of which the following is a specification.

This invention relates to gas igniting devices of the character wherein an element having catalytic action is depended on to 10 ignite gas issuing from burners, and my present improvement is directed to a portable device including a body member, a portion to which the igniting substance is attached, means whereby said igniting element is normally inclosed to exclude therefrom the deleterious influence of the atmosphere, and automatically retractable means whereby the igniting element may be manually 15 projected from its closure means when it is 20 projected from its closure means when it is to be applied in service.

Other features and advantages of my invention will hereinafter appear.

In the drawing:—

25 Figure 1 is a side elevation of the device, partly in longitudinal section.

Fig. 2 is an enlarged partial view of the device in longitudinal section, showing the igniting element projected for service, and 30

Fig. 3 is a section on the line 3—3 of Fig. 1.

In carrying out my invention I provide a body member 1, which may be circular in cross-section, its end portion 2 being somewhat enlarged, for a purpose to be referred to hereinafter, and its end 3 of slightly tapering form, bounded by a shoulder 4. Said body member 1 has an axial orifice extended therethrough, to loosely receive a 35 rod or straight, stout length of wire 5, longer than body portion 1, that terminates, at one end, in a handle 6, here shown in the form of a ring, capable of receiving the thumb or a finger of the user.

40 The opposite end of rod 5 axially engages a short, cylindrical block or plug 7, that limits the outward movement of said rod; and a helical spring 8 surrounds the rod 5, between the body end portion 2 and handle 6, to hold the rod extended beyond the body member, at one end thereof, against the limitation provided by plug 7 bearing against the other end of said body member.

The plug 7 is fitted securely within the

open end of a cylindrical casing 9, whose 55 outer end 10 is closed, and whose wall is provided with a series of perforations 11. Said cylinder contains the igniting element, which, as usual, may consist of fine platinum strands 12, wrapped about a frame 13, 60 and carrying a pellet of platinum black, or the like, as 14.

In assembling, it is my practice to employ a frame 13 of suitable length, to be placed within cylinder 9, so that when the 65 plug 7 is fitted to said cylinder, to close it, the frame 12 will fit tightly against the cylinder end 10 and the plug end, to be thereby localized and held against movement. For, if the frame 13 were loose within its casing, 70 the slender platinum strands it carries would be liable to rupture.

An outer cylinder or sheath 15, open at both ends, is fitted at one end upon the cylindrical end 3 of the body member, whose 75 slightly tapered form enables a snug and tight joint to be effected between these members; and their union may be rendered more secure as by spinning an annular groove 16 about cylinder 15 for embedment in the 80 surface of end 3.

The cylinder 15 is of sufficient length to be co-extensive with the casing 9, when the rod 5, which carries said casing, is in its normal, retracted position through the tension 85 exerted by spring 8; but, by urging rod 5 through body member 1, thereby contracting spring 8, the casing 9 will be projected and exposed beyond cylinder 15, and in this condition it can be introduced into a flow of 90 gas from a burner for igniting purposes.

The rod 5 carries the washers 17, respectively at opposite ends of the spring 8, to serve as seats for spring 8, one of said washers lying against the body end portion 2, and 95 the other lying against the rod handle 6.

The device is easily manipulable with one hand by insertion of the thumb or a finger within handle ring 6, and by grasping the body member forwardly of its enlarged portion 2, with the fingers, or with the thumb and fingers, whereby sufficient purchase is found for convenient operation of the device.

By reason of the normally inclosed state 105 of the catalytic igniting element its period of usefulness is greatly prolonged, and it is always kept in serviceable condition.

Variations within the spirit and scope of my invention are equally comprehended herein:

I claim:—

- 5 1. In a gas igniter, in combination, a body member having an axial orifice, a cylinder extended at one end of said member, a rod of greater length than said member and loosely entered in the axial orifice thereof, a perforated, closed casing, an igniting element therein, said plug serving as the closure for said casing and being carried by said rod at one end thereof, and said casing 25
- 10 10. In a gas igniter, in combination, a body member having an axial orifice, a cylinder extended at one end of said member, a rod of greater length than said member and loosely entered in the axial orifice thereof, a perforated, closed casing, an igniting element therein, said casing being carried by said rod at one end thereof, and fitting within said cylinder to close its orifices, a handle at the other end of said rod, and a helical 30
- 15 spring upon said rod, said spring lying between said handle and body member, and serving to extend said rod to thereby hold said casing normally ensheathed within said cylinder. 35
- 20 2. In a gas igniter, in combination, a body

member having an axial orifice, a cylinder secured to and extended from one end of said member, a rod of greater length than said member and loosely entered in the axial orifice thereof, a plug secured to said rod, a 25 perforated closed casing, an igniting element therein, said plug serving as the closure for said casing and being carried by said rod at one end thereof, and said casing slidably fitting within said cylinder, a handle at the other end of said rod, and a helical spring upon said rod, said spring lying between said handle and body member, and serving to extend said rod to thereby hold said casing normally ensheathed within said cylinder.

Signed at the borough of Manhattan, in the city, county and State of New York, this 19th day of April, A. D. 1921.

JOSEPH A. ZAHN.
